THOMAS A. THOMAS AND WADIE F. HAWIE, SR., OF HUNTINGTON, WEST VIRGINIA

COMBINED FROG AND SECTION INSULATOR

Application filed July 6, 1929. Serial No. 376,462.

This invention relates to improvements in trolley lines, and its general object is to provide a combined frog and section insulator with manually operated switches for controlling the circuits in the main and branch lines from the frog, whereby the operator can control the circuits in accordance with the course of travel over the lines.

A further object of the invention is to provide a device of the character set forth, that is primarily designed for sectional trolley wires used in mines and industrial plants, and the device is provided from parts that are detachable and held together by bolt and nut connections, with the result that damaged or worn parts can be replaced and in some instances without removing the device in its entirety from its hanger, wherefore service can be substantially maintained under practically all conditions.

Another object of the invention is to provide a frog and switch section of the insulated type, for trolley wires, that is formed in a single unit and which can be installed in an easy and expeditious manner, is inexpensive to manufacture and maintain and is extremely efficient in operation and service.

This invention also consists in certain other features of construction and in the combination and arrangement of the several parts, to be hereinafter fully described, illustrated in the accompanying drawings and specifically pointed out in the appended claims.

In describing our invention in detail, reference will be had to the accompanying drawings wherein like characters denote like or corresponding parts throughout the several views, and in which:

Figure 1 is a side elevation of the device forming the subject matter of the present invention.

Figure 2 is a top plan view thereof.

Figure 3 is a bottom plan view showing parts in full and dotted lines.

Figure 4 is a sectional view taken approximately on line 4-4 of Figure 3, looking in the direction of the arrows.

Referring to the drawings in detail, the reference numerals 1 and 2 indicate blocks of insulating material, the block 1 being relative-

ly longer than the block 2, with the block 2 arranged at an inclination with respect to the block 1 and disposed between the blocks 1 and 2 is a wedge member 3 that is held in operative position through the instrumentality of a bolt and nut connection 4 which extends through the blocks for holding the latter associated as clearly shown in Figure 2 of the drawings. The bolt and nut connection 4 has its head and nut countersunk in the respective blocks as shown.

Secured to the upper side of the block 1 adjacent each end thereof, as well as adjacent one end of the block 2 through the medium of screws passing through the flanges 5 thereof are bracket members 6 which have their bodies disposed in spaced relation with respect to the blocks, with slots 7 formed therein for the purpose of accommodating the shanks of nuts 8 that are loosely mounted between the bracket members and blocks. The shanks receive hanger members whereby the device can be supported from cables or other suitable means as well as the roof of a mine as will be apparent.

Secured to the bottom faces of the blocks and in a manner to underlie the juncture thereof is a bridging casting 9 which is substantially flat and held fixed to the blocks through the medium of screws 10.

This casting has formed with its side edges guard rails or flanges 11, and while one of these side edges is disposed substantially parallel with the block 1, the opposite side edge is disposed parallel with the block 2, with the result that the guard rails are arranged at an angle with respect to each other as best shown in Figure 3, due to the arrangement of the blocks. Formed integral with the casting 9 is a U-shaped cap member 12, arranged upon opposite sides of the block 1 and the adjacent end thereof as best shown in Figure 2, and formed with this cap member as well as the body of the casting is a trolley carrier 13 which extends a considerable distance beyond the outer end of the casting as well as inwardly of the outer end as best shown in Figure 3, and this trolley carrier 13 has its inner portion disposed substantially midway between the opposite sides

of the casting. The carrier is provided with a bore for a portion of its length for the purpose of receiving one end of a trolley wire 14 which is held therein through the instrumentality of bolts 15. The body of the casting has also formed therewith trolley carriers 16 and 17, the carrier 16 being disposed in alignment with the carrier 13, while the carrier 17 is arranged at an angle with respect thereto, and the trolley carriers 16 and 17 are disposed in spaced relation with respect to each other, as well as with respect to trolley carrier 13.

Secured to the end of the block 1 opposite the end having the U-shaped cap member secured thereto is a cap member 18 including a front, a top and a side. The cap member 18 is fixed to the block by bolt and nut connections 19 and formed with the top and front thereof is a trolley carrier 20 which is aligned with the trolley carriers 16 and 13. The trolley carrier 20 is provided with a bore to receive a trolley wire in the same manner as does the carrier 13. Secured to the outer end of the block 2 is a cap member 21 that likewise includes a front, a side and a top, and formed with the front and top is a trolley carrier 22 which is aligned with the carrier 17 and the carrier 22 is provided with a bore to receive a trolley wire of a branch line or the like; the trolley carrier 22 is likewise secured to the block 2 through the medium of bolt and nut connections that pass through the block and the side member 35 as shown.

The casting 9 has formed therewith a side strip 23 which rises from the casting inwardly of one edge thereof, and this side strip is provided with a recess as best shown in Figure 1. Formed integral with the side strip 23 is an elongated piece 24 that has secured thereto and extending therefrom spaced parallel clips 25 for the purpose of receiving a blade 26 between the same, and the blade has one of its ends pivotally secured to clips 27 secured to a piece similar to the piece 24 and which is formed with the cap 18.

The blade 26 has secured to its opposite end a handle 28 arranged at an angle with respect to the blade and said handle is formed from rubber or other insulating material. The blade and clips constitute a switch as will be apparent, and secured to the blade by suitable detachable means such as bolt and nut connections is one of the arms 29 of a bracket 30, while the opposite arm 31 has formed therewith a trolley carrier 32 adapted to be aligned with the carriers 16 and 20.

Arranged upon the opposite side of the device and formed with the casting 9 is a plate 33 disposed in contacting engagement with the block 2 at one end, and this plate 33 has formed therewith a piece from which

extend clips 34 that are arranged in spaced relation with respect to each other to slidably receive one of the ends of a switch blade 35, while the opposite end of the switch blade is pivotally secured between clips 36 extending from a piece formed with the cap member 21. Secured to the blade 35 intermediate its ends is one of the arms of a bracket 37, while the opposite arm has formed therewith a trolley carrier 35 which is adapted to be disposed in registration with the carriers 22 and 17, when the switch which is provided with the switch blade 35 is in closed position as shown in full lines in Figure 3. However, when the switch blade is disposed to open position as shown in dotted lines, the carrier 35 is arranged out of registration with respect to the carriers 22 and 17, and the circuit from the main line to the branch line of the wires will be opened.

When the switch blade 26 is disposed in open position, the circuit in the main line is open and the carrier 32 is disposed out of alignment with respect to the carriers 16 and 20. The switch blade 35 is likewise provided with a handle indicated by the reference numeral 36, and this handle is also formed from insulating material.

From the above description and disclosure of the drawings, it will be obvious that we have provided a combined frog and section insulator with switches for controlling the circuits therethrough, that is formed in a single unit, with the parts thereof detachable, with the result the installation and maintenance will be reduced to a minimum.

It is thought from the foregoing description that the advantages and novel features of our invention will be readily apparent.

We desire it to be understood that we may make changes in the construction and in the combination and arrangement of the several parts, provided that such changes fall within the scope of the appended claims.

What we claim is:

1. A combined frog and section insulator of the character described comprising a pair of blocks formed from insulating material, one block being relatively longer than the other with the short block being arranged at an inclination with respect to the other, a wedge member between said blocks, means for securing the blocks associated and passing through the wedge member, electric switch means carried by each block, trolley carriers associated with said blocks, and trolley carriers cooperating with the trolley carriers first mentioned and carried by said switch means.

2. A combined frog and section insulator comprising a pair of blocks formed from insulating material, one of said blocks being disposed at an inclination with respect to the other block, means for securing the blocks together accordingly, a bridging casting se-

cured to the blocks at the juncture thereof, guard rails formed with said bridging casting, a cap formed with said bridging casting and disposed about the end of one of said blocks, a trolley carrier formed with said bridging casting and extending beyond the last mentioned end, trolley carriers carried by the opposite end of the last mentioned block and the other block respectively, trolley carriers formed with the bridging casting in a line with the second mentioned trolley carriers, cap members having formed therewith the last mentioned trolley carriers, and secured to said blocks, electric switch means carried by said blocks, and trolley carriers carried by said switch means and adapted to be aligned with other trolley carriers.

3. A combined frog and section insulator comprising blocks secured together, one of said blocks extending from the other block at an inclination with respect thereto and from substantially midway the ends thereof, cap members secured about the ends of said blocks, trolley carriers formed with said cap members and extending beyond the ends of said blocks, a bridging casting, trolley carriers formed with said bridging casting, the trolley carriers of one cap member being formed with said bridging casting, electric switch means and trolley carriers carried by said switch means for cooperation with other of said trolley carriers.

4. A device of the character described comprising a pair of blocks secured together with one block disposed at an inclination with respect to the other, cap members secured to the ends of said blocks, a bridging casting having one of said cap members formed therewith and disposed at the juncture of the blocks with each other, said bridging casting extending beyond the sides of the blocks, guard rails formed with said bridging casting, trolley carriers formed with said bridging casting, trolley carriers formed with the other cap members, means formed with said cap members and bridging casting and disposed upon the outer sides of said blocks, clips formed with the last mentioned means in parallel pairs, switch blades having one of their ends pivotally secured to some of the pairs of clips, and movable for engagement with the other pairs, insulating handles for said blades, and trolley carriers carried by said blades for the purpose specified.

55 In testimony whereof we affix our signatures.

THOMAS A. THOMAS.
WADIH F. HAWIE, Sr.
